United States Patent Office.

JOSEPH DELANEY, OF ASHLAND, PENNSYLVANIA.

Letters Patent No. 91,093, dated June 8, 1869.

APPARATUS FOR RAISING AND DUMPING COAL.

The Schedule referred to in these Letters Patent and making part of the same.

To all whom it may concern:

Be it known that I, JOSEPH DELANEY, of Ashland, in the county of Schuylkill, and State of Pennsylvania, have invented an Improvement in Raising and Dumping Coal, Ore, &c.; and I do hereby declare the following to be a full, clear, and exact description of the same.

My invention consists in the combination of a certain arrangement of rails at the top of a colliery or other slope, with a peculiar car, (an improvement upon that for which Letters Patent were granted to J. W. Bancroft on the 8th day of January, 1867,) the wheels of which are so arranged with respect to the said rails, that the car, after being raised to the top of the slope, shall be automatically tilted and its load discharged; all of which is fully described hereafter.

In order to enable others skilled in the art to make and use my invention, I will now proceed to describe its construction and operation, reference being had to the accompanying drawing, which forms a part of this specification, and in which—

Figure 1 is a sectional elevation of a portion of a mine-slope, with my invention;

Figure 2, the same, showing the method of tilting a car, after it has been raised to the top of the slope;

Figure 3, a rear view of the upper portion of fig. 2;

Figure 4, an enlarged sectional view of one of the rear wheels of the slope-car;

Figures 5 and 6, modified forms of wheels; and

Figure 7, a diagram representing a modification of my invention.

Similar letters refer to similar parts throughout the several views.

A represents a portion of a mine-slope, on which is laid a track B, the latter, after reaching the highest point, x, of the slope, being continued downward at a moderate angle, so as to form a short inclined plane, a.

Two rails c c, arranged at the same angle, and forming a continuation of the track B, extend from the point x of the slope to the top of a vertical frame, F, these rails being placed outside of the rails of the track B, and being slightly elevated above the same at their lower ends, as shown in the drawing.

The car H, by which the coal, ore, or other material is raised up the slope A, is mounted upon flanged wheels I and I', arranged to run upon the track B; and the operating-rope or chain e, which passes over a pulley, e, of the frame F, is connected to a yoke, L, hung to lugs d d at the opposite side of the said car, as fully described in the aforesaid patent of J. W. Bancroft, of January 8, 1867.

In addition to the hind wheels I' of the car, which, in the present instance, are of somewhat larger diameter than the front wheels I, there are upon the same axle j, figs. 3 and 4, and outside of the said hind

wheels, two smaller flanged wheels k k, which, when the car reaches the top of the slope, are arranged to run upon the rails c c, as will be hereafter described.

The operation of the above arrangement is as follows:

The car having been lowered to the bottom of the slope, is filled with the coal or other material to be elevated, and is then raised, by means of the hoisting-gear, to the highest point x, the front wheels of the car then passing between the rails c, and beginning to descend the inclined plane a, which the hind wheels are prevented from doing by reason of the overhanging loose wheels k k, these latter being caused to mount the rails c c, as best observed in fig. 2, until the rear end of the car is sufficiently elevated to discharge the coal from the front end of the same into a chute, or directly into a boat, car, or other receptacle placed to receive it.

It will be observed that the yoke L is connected to the car at a point so far back that it aids considerably in tilting the same, when its angle, with respect to the said car, is changed, as seen in fig. 2.

After the load has been discharged, and the operating-rope or chain e permitted to slacken, the car will right itself, and by its own weight alone return to the slope, the rear end of the car first descending from the rails c, and then, passing down the slope until the front wheels are withdrawn from the inclined plane a, and the car again assumes the angle shown in fig. 1.

The modification of my invention shown in fig. 7 represents a plan, by which the car, after being raised to the top of the slope, and tilted, can be conveyed to any convenient point before discharging its load; but in this case the inclined front of the car should be provided with a suitable door or trap for preventing the discharge of the contents before the proper time.

The car might also be drawn horizontally, after reaching the top of the slope, and not tilted until it had arrived at the point where the load was to be discharged.

Although I prefer, especially in steep slopes, that the hind wheels of the car should be of considerably increased diameter, as described in the patent of the aforesaid J. W. Bancroft, yet this is not absolutely essential in carrying out my invention; nor is it necessary that the supplementary wheels k should be loose and separate from the wheels I', as they can be readily cast on to the same, as seen in fig. 5, or the hind wheels may, if desired, be merely increased in width, as illustrated in fig. 6; the object in every case being to cause the front wheels to pass between the rails c and the hind wheels, (or supplementary wheels upon the rear axle,) to run upon and mount the said rails.

Although my invention is especially designed for

use in colliery-slopes, it will be evident that it is equally applicable for raising and dumping coal, or any other material.

I claim as my invention, and desire to secure by Letters Patent—

In combination with the slope-track B and with rails c c, arranged outside of and forming a continuation of the same, a car, H, the wheels of which are so arranged, with respect to the said track and rail c, that, after reaching the top of the slope, the said car

shall rest both on the rails B and C, and shall be automatically tilted, and its load discharged, all substantially as herein set forth.

In testimony whereof, I have signed my name to this specification, in the presence of two subscribing witnesses.

JOSEPH DELANEY.
